UNITED STATES PATENT OFFICE.

ALBERT BIE, OF WINTERTHUR, SWITZERLAND, ASSIGNOR TO BUSCH-SULZER BROS.-
DIESEL ENGINE COMPANY, OF ST. LOUIS, MISSOURI, A CORPORATION OF MISSOURI.

ENGINE-CYLINDER.

1,260,859.

Specification of Letters Patent. Patented Mar. 26, 1918.

Application filed March 8, 1915. Serial No. 12,743.

To all whom it may concern:

Be it known that I, ALBERT BIE, a citizen of the Kingdom of Norway, residing in Winterthur, Switzerland, have invented the 5 following-described new and useful Improvement in Engine-Cylinders.

This invention relates to cylinder construction for internal combustion engines, and is concerned particularly with the heads 10 thereof, being designed more especially, though not necessarily exclusively, for constant pressure oil engines having their fuel injection valves arranged centrally in the heads. The object is to provide a construction of head suitable for these, and other, engines which affords access to the cooling space in the head, simplifies repair, reduces expansion strains, and improves the cooling.

In the accompanying drawings: 15

20 Figure 1 is a longitudinal section through the head and adjacent portion of the body of the cylinder;

Fig. 2 is a bottom plan view of the head, and Fig. 3 is a longitudinal section through 25 a head with a slightly modified construction.

The drawing shows a cylinder of a Diesel engine comprising a body *b* having a water-cooling space in its wall, and a hollow head 30 *a* formed separately from the body and also containing a water-cooling space *m*. Within the cylinder between the head and the piston *p* is the combustion-chamber *r*, its size varying according to the position of the. 35 piston.

The head is in this instance provided with three valve sockets *o*, *e* and *f* passing through the cooling space *m*, the socket *o* being central and preferably separate from 40 the head and the sockets *e* and *f* at opposite sides being preferably integral. The socket or tube *o* is received in an opening *g* in the top of the head and contains a fuel injection valve, which comprises a housing or casing 45 *s*, containing a valve proper *t*, the device being of known character, operating to atomize and inject the oil into the combustion chamber by a blast of air under high pressure when the part *t* is unseated. The interiors of the sockets *e* and *f* are designed 50 to receive combustion air and starting air valves, *x* and *z* respectively, and terminate in openings *c* and *d* through the inner wall *v* of the head, which wall partially separates 55 the cooling space *m* in the head from the

combustion chamber *r*, and has its central portion cut away at *i*, affording an opening into the cooling space around the fuel valve and socket *o*. This opening is closed by a piece *l*, which is applied over the opening 60 against the inner side of the head, after the manner of a man-hole cover, constituting in effect a removable section of the inner wall of the head, closing off the cooling space *m* from the combustion chamber within a limited area around the spot where the fuel valve delivers the atomized fuel into the compressed air in the cylinder. In order to admit the fuel the closure piece is formed 65 with a central aperture *k*, preferably flared 70 toward the combustion chamber, as shown.

In the embodiment of the invention shown in Figs. 1 and 2 the piece *l* has a boss *w* projecting inwardly of the head and screwed firmly at *n* to the socket *o*, the outer portion 75 of the piece bearing tightly against the wall *v*; but instead of being screwed only centrally the closure piece may be fastened at more than one point if desired. As shown, the said piece is not only retained by the fuel valve socket, but also serves to hold the latter in position by drawing a flange or shoulder *h* thereon against the upper part of the head.

In the embodiment of the invention shown 85 in Fig. 3 the boss *w* carries a flange *a'*, which is fastened with bolts *b'* against the socket *o*.

The closure piece is readily replaced in event of injury, may be made of specially resisting material, and the fact of its being free for radial expansion materially reduces the heat tension in the head. It also affords access to the interior of the head, for clearing the same of accumulations, and being a 90 separate piece may be finished off smooth on the inside surface, thereby rendering the cooling more effective by lessening the possibility of adhesion of scale and steam bubbles at the region of most intense heat and 95 consequently greatest likelihood of formation of deposits.

It will be understood that the drawing does not purport to show features and details unessential to the invention, and that, 100 for example, wherever joints should be made tight in practice the usual expedients may be resorted to in actual construction.

I claim:

1. In an internal combustion engine cylin- 110

- der, a hollow water-cooled cylinder head containing a fuel injection valve casing and having an inner wall with a central opening around said casing and a removable cover for said opening, this cover being smaller in diameter than the end of the combustion chamber and being applied against the combustion-chamber face of said wall.
2. In an internal combustion engine, a cylinder having a hollow water-cooled head provided with an opening through its inner wall, and a separate piece applied to the inner side of the head closing said opening and free from the sides of the cylinder, said piece being secured at its central region and being free to expand radially.
3. In an internal combustion engine, a hollow water-cooled cylinder head having a fuel valve socket passing through the cooling space in its interior, said head being formed with an inner wall separating said cooling space from the combustion space and provided with a central opening through said wall around said valve socket, and a separate small cover closing the opening around the socket and itself provided with an opening for the admission of fuel.
4. In an internal combustion engine, a cylinder head hollow for circulation of cooling water, a hollow valve-containing member passing through the head, and a separate removable piece closing off the cooling space in the head from the combustion space and held in place by fastening means engaging said valve-containing member.
5. In an internal combustion engine, a cylinder head containing a cooling space with an opening in its wall adjacent the end of the combustion chamber, a separate hollow valve-containing member passing through said space with its inner end standing in said opening, and a closure plate for said opening united toward its center with the valve-containing member and free for radial expansion.
6. In an internal combustion engine, a

cylinder head containing a cooling space and having an inner wall provided with an opening, a separate hollow valve-containing member passing through the head, and an apertured small cover for said opening fastened to said valve member, whereby both the cover and the valve-containing member are held in position.

7. In an internal combustion engine cylinder, a head containing a space for circulation of cooling water and having an inner wall separating said cooling space from the combustion chamber, said wall having an opening, a fuel valve in the head, and a removable small cover piece held against the combustion-chamber face of said wall with freedom for radial expansion and forming a closure between said cooling space and the combustion space around the fuel valve.

8. In an internal combustion engine, a cylinder having a head containing a space for circulation of cooling water, a valve socket passing through said cooling space, the head having an inner wall formed with an opening around said socket, and a closure for said opening fixed to said socket and at its surface adjacent its outer edge bearing against the inner side of the head with freedom to move thereon.

9. In an internal combustion engine, a hollow water-cooled head containing a plurality of valve sockets and having an inner wall formed with an opening around one of the sockets, and a separate small cover piece centrally apertured and applied to the inner face of the head closing said opening, the other valve sockets opening through the inner wall beyond the edge of said cover piece.

In testimony whereof, I have signed this specification in the presence of two witnesses.

ALBERT BIE.
